Inventor:

George F. Stewart

UNITED STATES PATENT OFFICE

2,234,149

HOSE HANDLING AND STORAGE APPARATUS

George F. Stewart, Scotia, N. Y.

Application December 19, 1938, Serial No. 246,659

1 Claim. (Cl. 242—157)

My invention relates to hose handling mechanisms and more particularly to a new and improved, fast and efficient mechanism for conveying lawn and garden hose to the cellar of a building structure when it is not in use.

In my Patent 2,135,736 I have described and claimed a novel apparatus which is to be mounted on the cellar window sash of a building structure and which is provided with a plurality of rollers for conveying a length of garden or lawn hose from outside the building into the normally relatively cool, dark and damp cellar when the hose is not in use and it is desired to store it. This arrangement serves to prolong the life of the hose and provides an easy arrangement for getting the hose out of the way and out of sight when it is not in use.

I have discovered, however, that the mechanism shown in the patent is not well adapted for use with different sizes of cellar windows and that a different size mechanism of the type shown in the patent must be made for each different size of window sash. Furthermore, this device is not readily adapted for use on either end of a cellar window sash so that separate right hand and left hand type units have to be made which are adapted respectively for use on the right hand and left hand ends of the window sash. Furthermore, it is usually desirable to ventilate cellars in the summer time and often screens are mounted on the outside of the cellar window frames so as to prevent the entrance of insects and vermin when the cellar windows are open. Screens are usually a different size than the window sash so that the device shown in the patent is not readily adapted to these different size window screens.

I have also discovered that when the hose is passed through the apparatus into the cellar the portion of the hose passing over the roller tends to oscillate or periodically change its direction by reason of the normal self-coiling action of the hose when it reaches the cellar floor or other surface on which it is to be stored. This motion of the hose tends to introduce a certain amount of objectionable friction because it tends to be restrained by the flanges on the rollers.

In accordance with my present invention I provide a new and improved apparatus for overcoming these difficulties. Thus, in accordance with one feature of my present invention I mount my apparatus on a plate which is in the shape of a right-angled triangle so that the right

angle thereof may be fitted into any corner of any size window sash or screen window frame. It thus may just as well be mounted on the right hand side as on the left hand side of the sash or frame. Furthermore, I mount the roller on a pivoted frame so that the position of the roller may readily adapt itself to changes in the angle of the hose as it passes over the roller and tends to coil itself in the cellar.

An object of my invention is to provide a new and improved hose handling apparatus.

My invention will be better understood from the following description taken in connection with the accompanying drawing and its scope will be pointed out in the appended claim.

In the drawing Fig. 1 is a front elevation of a preferred form of my invention with the cover for the roller opening removed, Fig. 2 is a similar view with the cover in place, Fig. 3 is an enlarged detailed view of the roller frame and roller, Fig. 4 is a side elevation of the roller frame showing its pivotal mounting, and Fig. 5 is a front elevation of the mechanism mounted in the upper left hand corner of a cellar window sash. Similar reference characters identify the same elements throughout the several figures.

Referring now to the drawing and first to Fig. 3, a rectangular frame 101 which may be made of any suitable material, such as butt-welded strap iron, has mounted therein a grooved roller 102 mounted on a rivet or bolt 103 passing through the sides of the frame. The roller may be made of any suitable material and I have found that wood may be used satisfactorily. The groove in the roller is substantially semi-circular in cross section and substantially corresponds in diameter to the diameter of ordinary garden hose. At the top and bottom of the frame there are provided rivets 104 and 105 which pass through rearwardly-extending flanges 106 and 107 at the top and bottom of an opening in a triangular plate 109, as shown in Fig. 4. The plate 109 may be made of any suitable material such as of sheet iron and one of its angles is a right angle, as shown in Fig. 1, which is adapted to be fitted into the corner of a window sash or screen window frame, as shown more clearly in Fig. 5 where it is shown mounted in the upper left hand corner of a cellar window sash. The two sides forming the right angle are provided with spaced openings through which screws or bolts may be passed for fastening the plate in place. These two sides may be of any desired length and may be equal or unequal in length so long as the longest side does not exceed the minimum di-

mension of the smallest standard size window sash or window screen. A catch 110 is mounted on the plate 109 for fastening in closed position a cover, for the roller opening in the plate, which 5 is fastened thereto by any suitable means such as by a chain 111. A stiffening flange 112 is provided on the cover 113 and this cover is also provided with a pair of tabs 114 which when the cover is in place extend downwardly and in back 10 of the lower edge of the roller frame opening in the triangular plate, as shown by the dotted lines in Fig. 2. Another flange 115 on the cover engages the catch 110 snugly when the cover is pushed shut.

15 The hypotenuse side of plate 109 has a rearwardly extending flange shown by the dotted line in Figs. 1 and 2. In this flange are a plurality of slotted holes through which suitable bolts or rivets 116 are passed for adjustably positioning and clamping an angle bar 117. When the mechanism is used on a window sash the side of the angle bar which extends outwardly may be raised or lowered by means of the slotted hole construction so that it provides support for the glass 20 which is fitted in the window sash. The window sash varies in thickness and the glass used therein varies in thickness and by means of this construction the device is readily adapted to different thicknesses of sash and thicknesses of glass.

25 30 If the device is used in a window screen frame the screening is passed between the rearwardly extending flange on the triangular plate and the flat side of the angle bar which is adjacent thereto so that when the bolts 116 are drawn up the screening will be securely clamped in place.

35 The apparatus may be used with a hose which is supplied with water from either an outside faucet (sill cock) or a faucet located in the cellar. In the former case the hose is withdrawn from the cellar nozzle first when it is desired to use it and is returned to the cellar nozzle last. Any suitable means may be clamped to the nozzle 40 for preventing it from passing through the opening and falling into the cellar. In the case

of an outside faucet the hose is returned to the cellar nozzle first and withdrawn therefrom nozzle last.

While I have shown and described a particular embodiment of my invention, it will be obvious 5 to those skilled in the art that various changes and modifications can be made therein without departing from the invention and therefore it is aimed in the appended claim to cover all such changes and modifications as fall within the true 10 spirit and scope of the invention.

What I claim as new and desire to secure by Letters Patent of the United States is:

An improved garden hose handling mechanism for installation on the cellar window sash or cellar window screen frames of existing building structures comprising, in combination, a plate in the shape of a right-angled triangle whose two sides which form the right angle thereof are shorter than the shortest dimension of standard 20 cellar window sash and cellar window screen frames, means for fastening said plate to a cellar window sash or cellar window screen frame with the right angle thereof fitted into a corner of the sash or frame, the hypotenuse of said plate 25 having an inwardly extending flange, an angle bar of substantially the same length as said hypotenuse, means for adjustably fastening one side of said angle bar to said flange so that the other side of said angle bar will support window 30 glass in sash of varying thickness when said mechanism is mounted on a cellar window sash and so that window screening can be clamped between said flange and said bar when said mechanism is mounted on a cellar window screen 35 frame, an opening in said plate, a frame fitted in said opening, means for pivotally mounting said frame in said opening, a grooved roller mounted in said frame for rotation on an axis which is perpendicular to the axis on which said 40 frame is pivotally mounted, and a movable cover for the opening in said plate.

GEORGE F. STEWART.
